UNITED STATES PATENT OFFICE.

CARL A. BROWN AND FLORENCE L. GRANT, OF FOSTORIA, OHIO, ASSIGNEES TO GENERAL ELECTRIC COMPANY, A CORPORATION OF NEW YORK.

DESIGN FOR A LIGHTING-FIXTURE.

46,426.

Specification for Design.

Patented Sept. 22, 1914.

Application filed July 29, 1914. Serial No. 853,959. Term of patent 14 years.

To all whom it may concern:

Be it known that we, CARL A. BROWN and FLORENCE L. GRANT, citizens of the United States, residing at Fostoria, in the county of Seneca and State of Ohio, have invented a new, original, and ornamental Design for Lighting-Fixtures, of which the following is a specification; reference being had to the accompanying drawing, forming a part thereof.

The figure is a view in elevation of a street lighting fixture showing our new design.

We claim:

The ornamental design for a lighting fixture as shown.

CARL A. BROWN.
FLORENCE L. GRANT.

Witnesses:

CHARLES L. GUERNSEY,
C. A. GUERNSEY.
